UNITED STATES PATENT OFFICE

FRANK E. DETCHON, OF DELTA, COLORADO.

AUTOMATIC CARRIER FOR ELECTRIC WIRES.

No. 798,602.

Specification of Letters Patent.

Patented Sept. 1,

Application filed August 4, 1904. Serial No. 219,526.

To all whom it may concern:

Be it known that I, FRANK E. DETCHON, a citizen of the United States, residing at Delta, in the county of Delta and State of Colorado, have invented a new and useful Automatic Carrier for Electric Wires, of which the following is a specification.

This invention relates to devices employed in the stringing of telephone, telegraph, and other wires or cables between buildings, poles, and other supports where an aerial conductor is usually first stretched between the two points of support and forms a base or support for the carrying of the wires or cables.

15 The principal object of the invention is to provide a small self-propelling carriage which may be mounted on the aerial conductor and may be used to carry wires from one support to another without danger of overturning.

20 A further object of the invention is to provide a device of this class in which the traction wheel or wheels will be held firmly to the supporting wire or cable, so as to avoid danger of slipping when the carrier is traveling

25 upgrade.

A still further object of the invention is to provide an improved casing for all of the working parts of the carrier, so that the mechanism of the latter will not be injured by contact with the branches of trees or other obstructions.

30 A still further object of the invention is to provide a carrier of such construction as to prevent falling of the carrier from the overhead support in case of derailment.

35 With these and other objects in view, as will more fully hereinafter appear, the invention consists in the novel construction and arrangement of parts hereinafter fully described, illustrated in the accompanying drawings, and particularly pointed out in the appended claims, it being understood that various changes in the form, proportions, size, and minor details of the structure may be 40 made without departing from the spirit or sacrificing any of the advantages of the invention.

In the accompanying drawings, Figure 1 is a longitudinal sectional elevation of a wire-carrier constructed in accordance with the invention. Fig. 2 is a sectional plan view of the same on the line *a a* of Fig. 1. Fig. 3 is a transverse sectional elevation of the carrier on the line *b b* of Fig. 1. Fig. 4 is a detail

perspective view of a portion of the illustrating the flap-locking device.

Similar characters of reference are employed to indicate corresponding parts throughout the several figures of the drawings.

The main portion of the supporting frame of the carrier includes longitudinal bars 1 and 2 at one side of the carrier being united by vertical bars 4, and bars 2 and 3, which form the lower portion of the frame, being united by a series of transverse bars 5, 6, and 7. In addition to the frame is in part formed of a casing which incloses all of the working parts and prevents injury to the mechanism from contact with tree branches and other obstructions. This casing is formed, preferably, of sheet metal and is tapered at its front end and, if necessary, at its rear end. The central portion of one side of the casing is open for its entire length, forming a longitudinal slot 9 to permit the carrier to be readily inserted on the overhead support *a*. This slot is closed by a flap or door 10, the upper edge of which may be secured to the upper portion of the casing in any suitable manner, as by the formation of interfitting tongues 11 on the adjacent edges of the flap or cover, these tongues being provided with openings for the passage of a wire or rod 12, which when forced in place serves to firmly lock the flap in position and hold the parts of the casing together and at the same time forms a complete casing around the overhead support, so that in case of derailment it will be impossible for the carrier to fall to the ground.

In the upper bar 1 of the frame and in the casing at a point opposite said bar are formed bearings for the support of transversely-disposed shafts 15, on which are mounted grooved wheels 16, that are placed on the overhead support *a*, and the grooves may be lined with rubber, leather, or other suitable material in order to increase the tractive force and avoid danger of slipping when the carrier is ascending grades. To the shaft of one of the wheels 16 is secured a pinion 17, which intermeshes with a gear 18, formed on or carried by a spring-barrel 19, that is carried by a shaft or arbor 20, also having bearings in the frame and casing. In the spring-barrel is a propelling-spring 21, which is wound by the operator before the carrier is placed on the sup-

the purpose of governing the speed of the carrier the gear 18 is connected by a gear 22 to an arbor 23, carrying a gear 24, which will regulate the speed of the carrier travels.

bar 6 of the lower portion of the frame pivoted two arms 25, connected at intermediate of their length by a cross-bar.

These bars are provided with bearings for the reception of a small roller 27, on which is mounted a roller 28, adapted to engage the under side of the overhead support α at a point between the two grooved wheels 16, and said roller 28 is held up in contact with the support by means of a spring 30, one end of which is secured to the frame 7, and the opposite end of said spring passing over the bar 6 is placed under the cross-bar 26, the stress of the spring being sufficient to maintain the carrying-wheels in engagement with the support α with sufficient force to enable the carrier to ascend the frame without slipping.

The lower rear portion of the frame members 2 and 3 serves as supports for a reel 30, on which a wire, cord, or cable may be wound.

Carried bodily from one point to another, or the arrangement may be such that one end of the wire, cord, or cable is secured to one support and is gradually unwound from the reel as the carrier progresses. The reel is connected by gearing to a shaft 33, having at one end a crank 31 and provided with a spring 34, one end of which is connected to a pin 35, the spring serving to turn the reel in winding up the cable and being in part rewound as the cable is paid up, so as to hold said cable or wire under tension. This spring must of course be weaker than the propelling-spring.

In using the device overhead support α , usually in the form of a wire or cable, is stretched from one building or support to another, and then after the cable or wire is wound on the reel 30' and the spring-motor is wound the flap 10 is lowered and the carrier placed on the support α . The flap is then closed and locked and the carrier is started, being propelled, by the unwinding of the spring, to the distant building or pole, at which point a second operator will remove the end of the wire from the reel and secure it in place and then return the carrier after rewinding for a second wire.

Having thus described the invention, what is claimed is—

1. A wheeled carrier arranged to travel on an overhead support, a casing wholly inclosing the wheels and movable parts of the carrier, said casing having a longitudinally-disposed slot for the admission of the support, and a hinged flap or door forming a part of the casing and serving to close said slot. 60

2. A wheeled carrier adapted to travel on an overhead support, a carrier-casing wholly inclosing all of the movable parts of said carrier, and tapering at its forward end in the direction of said support, the casing being provided with a longitudinal slot for the admission of the support, and a hinged closing-flap forming a part of said casing and adapted to close the slot. 65 70

3. In a device of the class specified, a frame, a plurality of supporting-wheels carried thereby and adapted to travel on an elevated support, means for imparting movement to one of said wheels thereby to propel the carrier, a spring-pressed operating-roller arranged to engage the support at a point between said wheels, and an inclosing casing within which all of the movable parts of the device are disposed. 75 80

4. The combination with a spring-propelled wheeled carrier arranged to travel on an overhead support, and provided with a slotted casing for the admission of the support, means for governing the speed of travel of the carrier, and a spring-wound wire-carrying reel supported by said carrier. 85

5. The combination with a wheeled carrier arranged to travel on an overhead support and provided with a slotted casing, of a motor-spring for propelling the carrier, a wire-carrying reel, and a winding-spring for the reel, said winding-spring being of less strength than the motor-spring. 90 95

6. The combination with a frame, of carrying-wheels journaled therein, a spring-wound reel also supported by the frame, a motor-spring for propelling the frame, and a casing inclosing the whole of the frame, wheels, and reel, said casing having a tapered forward end and being provided at one side with a slot for admitting an overhead support. 100

In testimony that I claim the foregoing as my own I have hereto affixed my signature in the presence of two witnesses.

FRANK E. DETCHON.
